(57) **CLAIM**

The ornamental design for a lighting fixture support arm, as shown and described.

DESCRIPTION

FIG. 1 is a top plan view of a lighting fixture support arm in accordance with a first embodiment of the present invention; FIG. 2 is a left side view of the lighting fixture support arm illustrated in FIG. 1; FIG. 3 is a front view of the lighting fixture support arm illustrated in FIGS. 1 and 2; FIG. 4 is a right side view of the lighting fixture support arm illustrated in FIGS. 1–3;

FIG. 5 is a bottom view of the lighting fixture support arm illustrated in FIGS. 1–4; FIG. 6 is a top plan view of a lighting fixture support arm in accordance with a second embodiment of the present invention;

FIG. 7 is a left side view of the lighting fixture support arm illustrated in FIG. 6; FIG. 8 is a front view of the lighting fixture support arm illustrated in FIGS. 6 and 7;

FIG. 9 is a right side view of the lighting fixture support arm illustrated in FIGS. 6–8; and, FIG. 10 is a bottom view of the lighting fixture support arm illustrated in FIGS. 6–9.

The broken lines are shown for illustrative purposes only and form no part of the claimed design.
